UNITED STATES PATENT OFFICE.

CHESTER A. McDONALD, OF PORT ARTHUR, TEXAS.

RAILROAD-CROSSING SIGNAL.

Application filed December 3, 1925. Serial No. 72,979.

This invention relates to the class of signals and pertains particularly to a railroad crossing signal.

The primary object of this invention is 5 the provision, in a manner as hereinafter set forth, of a railroad crossing signal designed to be operated by a vehicle approaching a railroad crossing, to sound a warning signal to a vehicle driver to caution him that 10 a railroad crossing is near at hand.

The invention contemplates the provision of an elongated bar member resiliently supported in a slot transversely of a roadway in such a manner as to project a slight distance above the surface of the roadway. 15 At each end of the rod cables are attached which lead upwardly into gong housings where they are attached to a trip mechanism by means of which a gong hammer may be 20 tripped to ring the gong in the housing when a vehicle wheel depresses and releases the bar extending across the roadway.

Another object of the invention is the provision, in a manner as hereinafter set forth, 25 of a railroad crossing signal which is of simple construction, strong and durable, having few moving parts to get out of order, and inexpensive to manufacture and set up.

The invention will be best understood 30 from a consideration of the following detailed description taken in connection with the accompanying drawings forming a part of this specification, with the understanding that the invention is not confined to any 35 strict conformity with the showing of the drawings but may be changed and modified so long as such changes and modifications mark no material departure from the salient features of the invention as expressed in 40 the appended claims.

In the drawings:—

Figure 1 shows the signal structure embodying this invention in elevation, also showing in transverse section a roadway in 45 which the lower portion of the mechanism is positioned.

Figure 2 is a transverse section taken upon the line 2—2 of Figure 1 and,

Figure 3 is an enlarged detailed sectional view taken transversely of the signal operating bar and certain of the supporting elements thereof.

Referring now to the drawings in detail wherein like numerals of reference indicate 55 corresponding parts throughout the several views, a portion of a roadway is indicated

at 1 and embedded in this roadway transversely thereof is an elongated housing formed of the side and end walls 2, bottom 3 and top 4. As shown in Figures 2 and 3 60 the top 4 is of materially greater thickness than the sides and bottom and is provided with a central longitudinally extending slot 5. This housing is so placed in the roadway that the surface of the top 4 comes flush with 65 the surface of the roadway as shown.

Secured longitudinally of the bottom 3 by means of a centrally apertured plate 6, is a series of vertically arranged cylinders 7, the cylinders being threadably secured in the 70 apertures of the plates 6, and the plates are secured to the bottom of the casing by means of the screws 8. The upper end of each of the cylinders is open but the opening is of less diameter than the diameter of the cylinder 75 and extending through this opening is an arm 9 which is carried by a piston 10 which is housed within the cylinder and adapted to reciprocate therein. Interposed between the piston 10 and the bottom 3 of 80 the casing against which the lower end of the cylinders 7 open, is a coiled spring 11 which normally acts, as shown in Figure 3, to maintain the pistons 10 in upwardly projected position thus forcing the arms 9 to 85 the upward limit of their movement.

The upper end of each of the arms 9 is threaded as indicated at 12 and the threaded ends of these arms are each extended into a shank 13 carried by retaining collar 14. 90 These retaining collars are in alignment longitudinally of the casing, and have extended therethrough the signal trip bar 15 which bar extends beyond the ends of the casing as is shown in Figure 1. The height 95 of the trip bar supporting members is such that substantially half of the trip bar extends above the surface of the top 4 and the roadbed 1 and unless some heavy body is passing over the trip bar to cause it to be 100 depressed the spring members 11 will cause the trip bar to be extended through the slot 5 at all times.

Each end of the trip bar 15 has a coupling member 16 threaded thereon and into this 105 coupling member a nipple 17 is threaded. On the nipple 17, on each end of the trip rod 15 there is fitted an upwardly extending arm 18 having an aperture through the extended upper end thereof, and securing 110 this arm 18 in position upon the nipple 17, is a cap member 19.

Mounted in the bases 20, of which there are two, one at each end of the trip rod 15, are upright posts 21, to the upper end of each of which there is adjustably secured by means of the clamp yoke and set screw 22 and 23 respectively, a gong encasing box 24. The boxes 24 are open upon their under-sides and are covered by means of the heavy screens 25.

10 Within each of the houses 24 there is secured a gong 26 adjacent which there is pivotally mounted a trip hammer 27 controlled by the pivoted trip arm 28. Extending from and connecting one end of this trip arm 28 with the apertured end of the arm 18 carried upon the trip bar 15, is a cable 29.

From the foregoing description it will be readily seen that upon the passage of a vehicle across the trip bar 15, the bar will be depressed against the tension of the springs 11 and will pull down upon the cable 29 thus tripping the trip arm 28 to allow the hammers 27 to strike the gongs 26. Warning is thus given to the driver of the vehicle which has depressed the trip bar 15 that some danger is ahead such as a railroad crossing, sharp curve or steep descent, and the driver can then be on his guard and proceed with more caution.

25 Having thus described my invention what I claim is:—

1. In a roadway signal of the character set forth, an elongated housing adapted to be embedded in a roadway transversely thereof and having a slotted top adapted to be arranged flush with the surface of said road, a longitudinal series of vertically positioned cylinders mounted in said casing beneath said slotted top, a resiliently sup-

ported piston within each cylinder and normally maintained in upwardly projected position therein, a vertical arm carried by each of said pistons, a trip bar arranged within and extending slightly above the slotted top of said casing above said vertical arms, means for connecting the arms to the bar for the support of the same, a signal gong supported over said trip bar at one end thereof, and a pull cable connecting one end of said trip bar with said signal gong and adapted to actuate the gong upon the depression of the trip bar by a vehicle.

2. In a roadway signal of the character set forth, means to provide a housing adapted to be fitted in a roadway transversely thereof and having a slotted top adapted to be arranged flush with the surface of said road, a longitudinal series of vertically positioned cylinders mounted in said casing beneath said slotted top, a coil spring housed in each cylinder, a piston within each cylinder normally projected upwardly by the spring therein, an arm carried by each piston and projecting upwardly from said cylinder, a trip bar arranged in and extending slightly above the top edge of said slot, a plurality of members carried by said bar, threaded connection between each member and the upper end of an adjacent arm, supporting said bar from said arms, a trip gong adjacent one end of said bar, and a pull cable connecting said bar end with said gong to trip the same upon depression of the bar.

In testimony whereof, I affix my signature hereto.

CHESTER A. McDONALD.
